UNITED STATES PATENT OFFICE.

ROBERT ALLISON HALL AND EDUARD A. GRIFFITH, OF BALTIMORE, MARYLAND, ASSIGNORS TO THE RAYMOND BUTTON COMPANY OF BALTIMORE CITY, OF MARYLAND.

BUTTON.

SPECIFICATION forming part of Letters Patent No. 642,042, dated January 23, 1900.

Application filed May 17, 1899. Serial No. 717,168. (No model.)

To all whom it may concern:

Be it known that we, ROBERT ALLISON HALL and EDUARD A. GRIFFITH, citizens of the United States, residing at Baltimore, in the State of Maryland, have invented certain new and useful Improvements in Buttons, of which the following is a specification.

This invention relates to improvements in buttons.

Among the objects of the invention are to provide a button of simple, cheap, and durable construction that can be readily attached to the fabric and which will be flexible when attached to the said fabric.

5 The invention is illustrated in the accompanying drawings, in which—

Figure 1 is a side elevation of the button attached to the fabric, the latter being in section. Fig. 2 is a vertical section of same.

o Similar figures of reference refer to like parts throughout the several figures.

1 designates the head of the button; 2, the shank; 3, the base, and 4 the stud. The head 1, shank 2, and base 3 of the button are all formed 25 of one continuous piece of wire. The shank 2 is formed by coiling the wire spirally until the desired length of shank is obtained, and the wire is then coiled into a flat head 1 of any desired diameter. The lower end of the 30 shank 2 is coiled into a base 3, which rests upon the fabric to which the button is to be attached, the fabric being gripped tightly between the base 3 and the base 5. The stud 4 is provided with a base 5 and also a neck or 35 recessed portion 6, into which the wire shank 2 is coiled, as shown in Fig. 2, to prevent the stud 4 from pulling out of the shank when the parts are secured to the fabric.

The button is secured to the fabric by inserting the stud 4 through the said fabric 7, and then the wire is coiled tightly around the neck or recessed portion 6 of the stud 4, forming a spiral shank 2, and is then formed into

the flat head 1, the lower end of the said shank 2 being brought down tightly against the fabric and formed into the base 3, as hereinbefore stated, or the head, shank, and base of the button may be completely finished and the stud 4 then forced through the fabric and into the wire shank, the coils of the wire taking into the recessed portion of the stud and holding the latter securely from pulling out of the shank.

If it is desired, a washer may be inserted between the base 3 and the fabric 7.

As shown in the accompanying drawings, the head 1 of the button is provided on its periphery with a metal band 8 to give it a finished appearance and also prevent the extremity of the wire from catching in the fabric.

It will be seen that by having the shank, head, and base 3 of the button formed of one continuous piece of wire the button will possess an elasticity when attached to the fabric 65 which in a majority of cases will prevent its being pulled off by reason of any strain that may be brought to bear thereon.

Having thus described our invention, what we claim is—

A button consisting of a head, 1, a shank, 2, and a base, 3, formed of one continuous piece of wire; a metal band, 8, around the periphery of the button-head to prevent the end of the wire from catching in the fabric; and 75 a stud, 4, having a recessed portion, 6, around which the shank is coiled to prevent the said stud from pulling out when the button is secured to the fabric.

In testimony whereof we affix our signatures in the presence of two witnesses.

ROBERT ALLISON HALL.
EDUARD A. GRIFFITH.

Witnesses:

GEO. E. TAYLOR,
CHAPIN A. FERGUSON.

Correction in Letters Patent No. 642,042.

It is hereby certified that the name of the second-mentioned patentee in Letters Patent No. 642,042, granted January 23, 1900, for an improvement in "Buttons," was erroneously written and printed "Eduard A. Griffith," whereas said name should have been written and printed *Edward A. Griffith*; and that the said Letters Patent should be read with this correction therein that the same may conform to the record of the case in the Patent Office.

Signed, countersigned, and sealed this 30th day of January A. D., 1900.

[SEAL.]

THOS. RYAN,
First Assistant Secretary of the Interior.

Countersigned:

C. H. DUELL,
Commissioner of Patents.
